US00D765591S

(12) **United States Design Patent** (10) **Patent No.:** **US D765,591 S**
West et al. (45) **Date of Patent:** **** Sep. 6, 2016**

(54) **PANEL SKIRT AND PHOTOVOLTAIC PANEL**

(71) Applicant: **SolarCity Corporation**, San Mateo, CA (US)

(72) Inventors: **Jack Raymond West**, San Rafael, CA (US); **Tyrus Hawkes Hudson**, San Rafael, CA (US); **Emil Johansen**, San Rafael, CA (US)

(73) Assignee: **SolarCity Corporation**, San Mateo, CA (US)

(**) Term: **14 Years**

(21) Appl. No.: **29/520,265**

(22) Filed: **Mar. 12, 2015**

Related U.S. Application Data

(63) Continuation of application No. 13/316,450, filed on Dec. 9, 2011, now Pat. No. 9,291,369, and a continuation of application No. 13/960,835, filed on Aug. 7, 2013.

(57) **CLAIM**

The ornamental design for a panel skirt and photovoltaic panel, as shown and described.

DESCRIPTION

FIG. 1 is a top front perspective view of a panel skirt and photovoltaic panel showing our new design;

FIG. 2 is a top view thereof;

FIG. 3 is a front view thereof;

FIG. 4 is a right side view thereof; and,

FIG. 5 is a left side view thereof.

The dashed broken lines in the figures show portions of the panel skirt and photovoltaic panel that form no part of the claimed design.

The dot-dash broken lines in the figures show boundaries that form no part of the claimed design.
